UNITED STATES PATENT OFFICE.

VICTOR ARDITO, OF HOBOKEN, NEW JERSEY.

CUSPIDOR.

No. 853,912.

Specification of Letters Patent.

Patented May 14, 1907.

Original application filed July 16, 1906, Serial No. 326,417. Divided and this application filed November 23, 1906. Serial No. 344,784.

To all whom it may concern:

Be it known that I, VICTOR ARDITO, a citizen of the United States, residing at Hoboken, in the county of Hudson and State 5 of New Jersey, have invented certain new and useful Improvements in Cuspidors, of which the following is a specification.

This invention relates to improvements in cuspidors, and is designed as an improvement 10 in that class of cuspidors wherein running water is used for the purpose of cleaning and keeping the same clean and fresh, and has for its objects the provision of a rotatable funnel-plate, means for causing said funnel-plate to rotate, means for automatically controlling the supply of water delivered to said cuspidor, and means for intermittently drawing off the water from said cuspidor.

To these ends the invention consists in the 20 novel construction, arrangement, and combination of the several parts of the device, as hereinafter described, illustrated in the drawing, and more particularly pointed out in the claims hereunto appended.

25 This application is, except in certain minor details, a division of my former application No. 326,417, filed July 16, 1906.

In the drawing: Figure 1 is a vertical sectional view of the device, illustrating the arrangement of the parts, means for rotating the rotatable funnel-plate, a basket below said funnel-plate, means for automatically regulating the flow of water to said funnel-plate, and means for drawing off the water 35 from said cuspidor. Figs. 2, 3, and 4 are enlarged detail views of the device.

Referring to the drawings, the numeral 1 indicates the body or casing of the cuspidor, and 2 supports on which said body or casing 40 is mounted. The numeral 3 indicates an annular frame adapted to set or rest, preferably, in a seat 4 in the top edge of said cuspidor body or casing 1, as shown, and is preferably provided with a groove 5, in which are 45 suitably mounted rollers 6, for a purpose hereinafter stated.

The numeral 7 indicates a funnel-plate having its upper surface provided with curved corrugations 8, for a purpose hereinafter 50 stated. The under surface of said funnel-plate near its outer periphery is provided with an annular groove or curved portion 9, which is adapted to set over and upon the tops of the rollers 6 in the groove 5 of the 55 annular frame 3, as shown, for the purpose

of providing means permitting the ready rotation of said funnel-plate, as is evident.

The numeral 10 indicates a suitable pipe, adapted to be connected with the house supply pipe, and is provided near its lower end 60 with an emergency and regulating valve 11, for the purpose of limiting the amount of water passed through said pipe, and also for the purpose of completely cutting off such flow when, for any reason, such may be desired. The opposite end of said pipe is connected with, preferably, an annular pipe or ring 12, by a suitable hinged cut-off valve 13, said ring or pipe being provided with a suitable aperture, or apertures, 14 through 70 which water is thrown against the corrugations 8 upon the surface of the funnel-plate 7, for the purpose of imparting to said funnel-plate a rotary movement, and also to wash said plate during said movement. Located 75 in said pipe 10 between the valves 11 and 13 is a safety valve 15, the casing of which has an arm 16 projecting into said body or casing 1 through an opening 17 in the side wall thereof. The arm 16 is provided with a 80 stem 18, one end of which is secured to said valve 15 and the opposite end projecting into said casing, as is evident. To the interior of the body or casing 1, adjacent to the opening 17, is a suitable bracket 19 to 85 which is hinged a rod 20, one end of said rod being adapted to carry a float 21 while the opposite end thereof is adapted to engage the stem 18 to close said valve to cut-off the water supply from the funnel-plate. 90

The numeral 22 indicates a siphon outlet pipe for drawing off the water from the interior of said cuspidor, when such water rises therein to the siphoning point.

The numeral 23 indicates a suitable 95 strainer or basket removably mounted in said cuspidor below the funnel-plate and above the highest possible level that the water can reach in said body or casing, and is for the purpose of catching and retaining solids, 100 such as matches, cigars, etc., to prevent them falling to the bottom of the cuspidor, and eventually being carried off through the drain pipe, thus greatly reducing the liability of said drain pipe becoming clogged or 105 stopped up. It frequently happens, however, in this class of cuspidors that the basket or strainer fails to wholly retain the solids, in which event they pass to the bottom of the receptacle and are drawn into the outlet 110

pipe and cause it to become choked or clogged, and consequently the water flowing into the 5 cuspidor would soon overflow and pass with all its filth onto the floor, and this certainty of overflow, in the event of clogging of the drain pipe is the chief, and as far as I am aware, the only objection to this class of cuspidors. To overcome this objection I have provided the automatically operated 10 valve 15 and its operating mechanism which will effectually cut-off the flow of water before an overflow can possibly occur. If it be desired to remove the rotary funnel-plate the annular ring or pipe 12 is swung up out 15 of its position above said funnel, which action by reason of the hinged cut-off valve will stop the flow of water into said ring or pipe 12, and permit the removal of said funnel-plate, without the necessity of operating 20 the emergency valve 11, as is evident.

The operation of the device is apparent and a further description thereof is thought to be unnecessary.

Having thus described my invention what 25 I claim is—

1. In a cuspidor of the character described, the combination with a body or casing having a seat in its upper top edge, and a drain pipe in its bottom, an annular frame having rollers mounted therein seated in said seat in the 30 top of said body or casing, and a funnel-plate mounted over said casing on and carried by the rollers in said annular frame, of a water supply adapted to project a jet of water

against said funnel-plate to cause the same to 35 rotate.

2. In a cuspidor of the character described, the combination with a body or casing having a seat in its upper top edge, and a drain pipe in its bottom, an annular frame having 40 rollers mounted therein seated in said seat in the top of said body or casing, and a funnel-plate mounted over said casing on and carried by the rollers in said annular frame, of a water supply, and an annular water distributing 45 ring having apertures therein and connected with said water supply by a pivotal cut-off valve, normally setting over and above said funnel-plate, and adapted to project a jet, or jets, of water against said funnel-plate to cause the same to rotate.

3. In a cuspidor of the character described, the combination with a body or casing having a seat in its upper top edge and a drain pipe in its bottom, an annular frame seated 55 in said seat, rollers mounted in said frame, and a funnel-plate having its concave surface corrugated mounted over the top of said casing and carried by said rollers mounted in said annular frame, of a water supply 60 adapted to project a jet of water against said funnel-plate to cause the same to rotate.

In testimony whereof I affix my signature, in presence of two witnesses.

VICTOR ARDITO.
